UNITED STATES PATENT OFFICE.

MICHAEL J. DALY AND THOMAS S. LEAKE, OF CHICAGO, ILLINOIS.

SASH-BALANCE.

No. 884,472.

Specification of Letters Patent.

Patented April 14, 1908.

Application filed August 12, 1905. Serial No. 274,010.

To all whom it may concern:

Be it known that we, MICHAEL J. DALY and THOMAS S. LEAKE, citizens of the United States, residing at Chicago, in the county of 5 Cook and State of Illinois, have invented a certain new and useful Improvement in Sash-Balances, of which the following is a specification.

Our invention relates to sash balances and 10 has for its object to provide new and improved constructions for devices of that class. The invention will be illustrated and described with reference particularly to the use of our novel construction of pulley in 15 sash balances and the like, and it is one of the objects of our invention to provide new and useful arrangements in such sash balances; but it will be obvious, of course, that the invention is capable of other applications.

20 The invention is illustrated in the accompanying drawings wherein

Figure 1 is an elevation of a window from within, parts being broken away; Fig. 2, a sectional view on line 2—2 of Fig. 1; Fig. 3, 25 a detail section through the pulley of Fig. 2; Fig. 4, a section on line 4—4 of Fig. 3; Fig. 5, an end or edge view of the pulley, and Fig. 6, a section similar to that of Fig. 3, showing a modification.

30 In the drawings, A represents a window frame of any ordinary construction, B the upper sash, and C the lower sash. In the stile D at each side of the window frame, are set the pulleys E E for the window cords. 35 These pulleys are of peculiar and novel construction.

Referring particularly to Figs. 3 and 4, the block of the pulley is preferably composed of a casting E¹ adapted to be set into the face of 40 the stile D and provided at its upper and lower end with screw holes for the securing screws E² E³. The casting E¹ is apertured at E³ for the sheave and backward from the aperture extend the side pieces E⁴ E⁵. Between these side pieces is secured the core F in any desired manner, as for example, by the rivets F¹ F². The sheave consists of a relatively thin annulus G which turns upon the core F. Preferably it is formed with a 45 groove for the cord H, as shown at G¹. In the modification shown in Fig. 6, the annular sheave G is provided with the teeth or cogs G². This latter form of pulley is made use of when a chain is used instead of a cord. The 50 pulley in either case consists of a core or axle of a diameter nearly as great as that of the

annular sheave. This, of course, results in considerable friction if the parts are properly made, when the sheave turns on the core. Preferably the side pieces E⁴ E⁵ extend back 60 so as to form the flanges E⁵ E⁶ which prevent the cord from slipping off the sheave. When a pulley thus constructed so as to develop friction between the parts bearing upon each other is used in a window, the result is that 65 the movement of the sash is braked in starting and stopping. A smooth, even action is gained thereby. The pulley as above described, as has been suggested, is adapted for use in a sash-balance. It may be used in 70 windows of any form of construction, but we consider it particularly useful in connection with the arrangement of the sashes and weights which we are about to describe.

Referring particularly to Figs. 1 and 2, we 75 have shown an arrangement by which the two sashes of the window are counterbalanced by a single weight. The cord H is secured at one end to the lower sash C in any preferred manner, as for instance, by means 80 of the staple H¹ and then extends upward over the right-hand pulley E¹, as shown in Fig. 2, then down around a movable pulley H² of any preferred sort, then up over the pulley shown at the left-hand side of Fig. 2, 85 its other end being secured to the upper sash by means of the staple H³. Connected with the pulley H² is the hanger H⁴ having a hook H⁵ to which is hung the weight J. It will be understood, of course, that this arrangement 90 may be duplicated on the other side of the window.

The advantages in simplicity and economy in balancing both the sashes by a single weight are, of course, obvious. The arrangement, however, has its disadvantages in so much as the movement of one sash is likely to disturb the other. The pulley of our invention obviates this difficulty by acting as a brake, through the development of friction 100 as above indicated. It also will compensate for any slight difference in weight between the sashes and their counterbalance and thus insure a smooth and steady movement of the sashes. In this respect the pulley can be 105 advantageously used in other connections and in other arrangements of window sashes than that shown herein.

The modification shown in Fig. 6 will, of course, operate in the same manner as the 110 form above described except that the cord H will be replaced by a chain.

In the claims we have used the word "cord" but we desire that this should be understood to include any chain or other like means for supporting the weight.

5. We claim:

1. In a sash balance, the combination of a window sash with a counterbalancing element, a cord and a pulley comprising a core and a sheave, said sheave having an extended bearing surface in contact with the core so as to develop braking friction between it and the core to brake the movement of the sash.
2. In a sash balance, the combination of a window sash with a counterbalancing element, a cord and a pulley comprising a core and a thin annular sheave, said sheave having an extended bearing surface in contact with the core so as to develop braking friction between it and the core to brake the movement of the sash.
3. In a sash balance, the combination of a window sash, with a cord, two pulleys each comprising a core and a thin annular sheave

mounted thereon as described, and a weight 25 hung in the turn of the cord between the two pulleys.

4. In a sash balance, the combination of two window sashes, a single cord attached to each of the sashes, a counterbalancing element, said sheave having an extended bearing surface in contact with the core so as to develop braking friction between it and the core to brake the movement of the sash.

5. In a sash balance, the combination of two sashes, a single cord attached at each end to one of the sashes, two fixed pulleys over which the cord runs, a counterbalancing weight hung from the turn in the cord between the pulleys, said pulleys comprising 40 each a core and a thin annular sheave mounted thereon as described.
